(57) **CLAIM**

The ornamental design for a booth, as shown and described.

DESCRIPTION

FIG. 1 is a front view of a booth showing our new design;
FIG. 2 is a top view thereof;
FIG. 3 is a right side view thereof;
FIG. 4 is a left side view thereof;
FIG. 5 is a back view thereof;
FIG. 6 is a bottom view thereof;
FIG. 7 is a perspective view thereof;
FIG. 8 is a cross-section view along line 8-8 of FIG. 1;
FIG. 9 is a cross-section view along line 9-9 of FIG. 2;
FIG. 10 is an enlarged view of a portion marked as 10 in
FIG. 8;
FIG. 11 is an enlarged view of a portion marked as 11 in FIG.
8;
FIG. 12 is an enlarged view of a portion marked as 12 in
FIG. 8;
FIG. 13 is an enlarged view of a portion marked as 13 in
FIG. 8;
FIG. 14 is an enlarged view of a portion marked as 14 in
FIG. 8;
FIG. 15 is an enlarged view of a portion marked as 15 in
FIG. 8;
FIG. 16 is an enlarged view of a portion marked as 16 in
FIG. 8;
FIG. 17 is an enlarged view of a portion marked as 17 in
FIG. 8;
FIG. 18 is an enlarged view of a portion marked as 18 in
FIG. 9;
FIG. 19 is an enlarged view of a portion marked as 19 in
FIG. 9;
FIG. 20 is an enlarged view of a portion marked as 20 in
FIG. 9;
FIG. 21 is an enlarged view of a portion marked as 21 in
FIG. 9;
FIG. 22 is an enlarged view of a portion marked as 22 in
FIG. 9;
FIG. 23 is an enlarged view of a portion marked as 23 in
FIG. 9;
FIG. 24 is an enlarged view of a portion marked as 24 in
FIG. 9;

(Continued)

FIG. 25 is an enlarged view of a portion marked as 25 in FIG. 9;

FIG. 26 is an enlarged view of a portion marked as 26 in FIG. 9; and,

FIG. 27 is an enlarged view of a portion marked as 27 in FIG. 9.

The broken lines in the drawings are for environmental purposes or enlarged views' bounds only and form no part of the claimed design. The dot-dash broken lines in FIG. 1 and FIG. 7 represent the bounds of the claimed design. The oblique shade lines in FIG. 1 and FIG. 7 represent a transparent area.

1 Claim, 27 Drawing Sheets
